METHOD AND APPARATUS FOR
BURNING OIL

Charles A. French, Riverside, Ill.

Application October 14, 1929, Serial No. 399,685

6 Claims. (Cl. 158—53)

This invention relates to a method of and apparatus for operating oil burning devices particularly designed for the utilization of heavy oils. More particularly the invention relates to a method of and an apparatus for initiating and continuing the vaporization and combustion of oil.

The principal object of the invention is to devise a method of and apparatus for initiating and maintaining the combustion of oils, particularly the heavier grades.

Another object is to initially vaporize the oil by one method and to subsequently and automatically vaporize the oil by another method. 15 These objects and others, which will be apparent from the detailed description to follow, are obtained by initially vaporizing the oil by partial combustion and, subsequently carrying on the vaporization by the utilization of sensible heat 20 from a portion of the gaseous products of complete combustion.

Inasmuch as hydro-carbons apparently burn only from the molecule, it is probably impossible for them to burn in any but the vapor or gaseous state. It follows that, to produce the blue flame of complete combustion, it is necessary that the fuel shall be in the vapor or gas state and mixed with air in or very nearly in the combining ratio. However, the vaporization of 30 heavy hydro-carbons has presented many difficulties, the major one being the tendency of the oil to decompose, forming residues of tar and coke.

In the so called atmospheric type of burner, such as the conventional plumber's torch, the fuel is boiled under pressure in a closed retort. This method of vaporization does not differ materially from the common method of cracking heavy hydro-carbons into light oils, tar and coke. 40 In practice, such a vaporizer becomes filled with tar and coke just as do the common oil stills. In the hot spot type of burner, the liquid fuel is spread upon a surface heated to a temperature high enough so that the liquid particles do not 45 wet it. The liquid particles assume spherical form and are kept from contact with the hot surface by the vapor formed underneath them. A vigorous current of air scrubs over the heated surface, removing the vapors as fast as they are formed. This method provides a fairly satisfactory form of vaporization.

In the method and apparatus of my invention, I propose to vaporize the oil by sensible heat from portions of the oil undergoing combustion. 55 In a process of this nature, it is obviously neces-

sary to initiate the vaporization by some other method. In my invention this problem is taken care of in such a way that the starting means is automatically cut off when the burner becomes heated sufficiently for complete combustion. This 5 is accomplished by distributing the oil in a vaporization chamber in a finely divided form, or a thin sheet, such as from a high pressure spray, or from a rotating disk, and igniting it by a spark or otherwise.

There will be a sufficient amount of certain constituents of the oil vaporized by the spray to maintain partial combustion, for which a requisite amount of air is supplied. The partial combustion products and any liquid fuel vaporized by 15 the heat developed are mixed with air for complete combustion and supplied to the main burner. The source of air to the main combustion burner is adapted to draw a current of gases from the flame side of the burner through the vaporization 20 chamber. It will thus be seen that as soon as ignition and complete combustion is brought about at the main burner, the gases which are drawn through the vaporization chamber are inert, thus stopping the partial combustion in 25 said chamber. Thereafter, vaporization is carried on by direct contact with the portion of the hot combustion gases which is conducted through the vaporization chamber.

In the drawing: 30
Figure 1 is a diagrammatic view showing one form of apparatus embodying my invention; and, Figure 2 is a similar view of a modification.

In the drawing, Figure 1, a vaporization chamber 1 houses a rotating disk 2 for distributing oil 35 in a finely divided form. The disk 2 is mounted on a hollow shaft 3 adapted to rotate the disk and to supply oil thereto. A plurality of small openings 4 at the bottom of the shaft 3 adjacent the disk serve to distribute oil thereto. The shaft 3 40 extends through the top of the vaporization chamber and is provided with an oil supply pipe 5 controlled by a valve 6. Means are also provided for driving the shaft, such as the pulley 7, diagrammatically indicated. A cylindrical in- 45 take throat 8 communicates with the flame side of a burner 9. The burner has a grating 10 lying substantially in a horizontal plane and a conical, upwardly extending grating 11 at the center thereof. Said gratings constitute discharging 50 means for gases to be burned. The intake throat 8 communicates with the conical portion of the grating. At the upper end the intake throat 8 is provided with an outwardly extending cone-like shield 12 which surrounds the disk 2 in close 55

proximity thereto. The bottom of the vaporization chamber 1 has a downwardly depending, cylindrical baffle 13 spaced from the intake throat 8 to form an annular passage therebetween. A cylindrical casing member 14, concentric with respect to the baffle 13 and spaced therefrom, is attached to the vaporization chamber and joins the intake throat at the bottom. A small opening 15 is provided adjacent the grating 11 as a firing opening, as will be hereinafter described. A pipe 16 communicates with the casing member 14 and with a Venturi-like throat 17 in a fan intake pipe 18. The fan intake 18 is provided with a valve 19. A fan 20, with which the intake 18 communicates, is adapted to draw gases through the pipe 16 and air from the atmosphere through the inlet 18 and deliver them to the burner gratings 10 and 11. A spark plug 21 provided with a source of current, not shown, extends through the vaporization chamber into the path of the oil being distributed by the disk 2. It will be noted that said disk has a slight upwardly turned flange 22 at the edge and that the shield 12 extends upwardly above the path which will ordinarily be followed by oil being distributed from the disk at its normal rate of operation.

The modification shown in Figure 2 is similar in general design to that shown in Figure 1, 30 which has been described in detail, but differs materially in the location of the component parts. In Figure 2, the burner grating 23 constituting discharging means for gases to be burned has a substantially horizontal portion and an inverted 35 conical section 24. A casing member 25 joins the grating at the outer edge of the face of the horizontal portion and encloses all the other elements making up the burner.

A hollow shaft 26, connected at the top with a 40 supply pipe 27 controlled by a valve 28, carries a distributing disk 29 at the lower end. Small openings 30 at the bottom of the shaft near the disk 29 serve to distribute the oil onto the disk. The shaft 26 also carries a centrifugal fan 31 attached to the shaft at a point spaced upwardly above the disk 29.

A substantially horizontal baffle plate 32 fits around the shaft 26 in a fluid-tight manner and extends radially therefrom, being circular in 50 shape. An inner casing member surrounding the baffle 32 has a substantially horizontal upper portion 33 spaced above the baffle 32 and terminating near the center thereof, and a lower, downwardly and inwardly extending portion 34 which 55 joins the top of the conical section 24 of the burner grating. The top portion 33 of the inner casing lies adjacent to the lower edge of the fan blades. At the center of the upper horizontal portion 33, an annular opening 26' is formed concentric with the shaft 26. A conventional fire screen 33' extends from the edge of the opening 26' down to the baffle 32. This screen extinguishes any flames coming from the initial vaporization by partial combustion of oil sprayed from 60 the disk 29.

The outer casing 25, previously described in connection with the burner grating, extends around the inner casing in spaced relation thereto with the top portion 35 lying adjacent to the 70 top edge of the fan blades. An air intake conduit 36 communicates with the upper, central part of the casing 25.

A spark plug 37 extends through the outer and inner casing members and through the baffle member 32 into the path of the oil distributed 75

from the disk 29 during normal operation of the device.

A small firing tube 38 communicates with the interior of the vaporization chamber formed by the baffle 32 and the casing 34 and with the 5 burner grating 23.

In the operation of the device of this invention in the modification shown in Figure 1, the disk 2 is put into motion and oil is delivered thereto through the hollow shaft 3. The finely divided 10 spray formed off the edges of the disk 22 is ignited by the spark plug 21. It will be found that even in the heavy oils there will usually be enough of certain of the lighter constituents vaporized to such an extent that they will ignite 15 under these conditions. If ignition cannot be brought about by a spark plug, other means, such as a torch, may be employed.

The fan 20 is put into operation, drawing air from the conduit 18 in amounts determined by 20 the setting of the valve 19 and gaseous products from the vaporization chamber through the pipe 16. A circulatory motion is set up by the circulation of the fan, which draws gases from the vicinity of the grating 11, up the intake throat 8, 25 through the vaporization chamber 1, around the baffle 13, and into the intake side of the fan. When the device is first put into operation, air will be drawn from the vicinity of the grating 11, and combustion will be supported in the vaporization chamber.

As the vaporization chamber becomes heated, the incomplete combustion will increase until substantially all of the oil will be vaporized, forming a rich combustible gas. The flames in the 35 vaporizer will expand in proportion until they extend down around the baffle 13. When this condition is reached, the flames will shoot out of the opening 15 and ignite the gaseous mixture being delivered through the grating. 40

As soon as complete combustion has spread over the face of the grating 11 and the grating 10, the gases being drawn therefrom up the intake throat 8 will be inert in the sense that they will not support combustion. The partial combustion which had been taking place in the vaporization chamber will be automatically stopped by the lack of combustion supporting gases and the vaporization thereafter will be continued by the utilization of the sensible heat 50 of burned products of complete combustion drawn from the flame side of the burner grating. 45

The operation of the modification shown in Figure 2 is substantially the same as that shown in Figure 1. The device is more compact, due to 55 mounting of the fan and disk upon the same shaft, and is more easily insulated to prevent radiation losses. The firing tube 38 differs somewhat from the firing openings 15 in the device shown in Figure 1, but it functions in the same 60 manner.

The drawing is merely illustrative of certain specific embodiments of my invention. It is understood that the claim to invention is limited 65 only by the scope of the method and article claims following.

What I claim is:

1. An oil burner comprising a vaporization chamber, a burner grating, means for supplying 70 air to said grating, means to supply fuel to said chamber, means to draw gases from the combustion side of said grating through the vaporization chamber and to discharge the resulting products through the grating, means for igniting 75

the fuel in the vaporization chamber, means for thereafter igniting the gaseous products being delivered through the grating, the combustion at the grating automatically stopping combustion in the vaporization chamber by causing only inert gases to be delivered thereto.

5. An oil burner comprising a vaporization chamber, a burner grating, a fan for distributing air and gases to said grating, a duct positioned 10 to draw gases from the vicinity of the grating on the flame side thereof through the vaporization chamber and to the fan, and means for distributing oil in said vaporization chamber.

6. An oil burner comprising a vaporization chamber, a burner grating, a fan for distributing air and gases to said grating, a duct positioned 15 to draw gases from the vicinity of the grating on the flame side thereof through the vaporization chamber and to the fan, means for igniting the 20 gases in the vaporization chamber, and means for igniting the air and gases being delivered through the burner grating from the combustion in said vaporization chamber.

7. An oil burner comprising a burner grating, a vaporization chamber, means for supplying fuel 25

to said chamber, means for distributing said fuel in a finely divided form, means for drawing hot gases from the burner grating through said vaporization chamber, and means for supplying the products obtained therefrom to the burner grating.

8. A method of burning liquid hydro-carbons which comprises partially burning the fuel to initiate vaporization thereof, mixing the products of the partial combustion and the fuel so vaporized 10 with air and completely burning said fuel and thereafter vaporizing the liquid fuel by suspending it in a portion of the hot products of complete combustion.

9. An oil burner comprising means for initially 15 vaporizing fuel oil by partial burning of the oil, means for supplying air sufficient for complete blue flame combustion, means for mixing the products of said partial burning and the oil so vaporized with said air, means for igniting said mixture, and means to thereafter vaporize the fuel oil by direct contact with a portion of the 20 hot products of complete combustion.
